UNITED STATES PATENT OFFICE.

JOHN MAIER, OF ST. LOUIS, MISSOURI.

CRIMPING MACHINE.

Application filed November 26, 1920. Serial No. 426,457.

To all whom it may concern:

Be it known that I, JOHN MAIER, a citizen of the United States, residing at St. Louis, Missouri, have invented a certain new and useful Improvement in Crimping Machines, of which the following is a full, clear, and exact description, such as will enable others skilled in the art to which it appertains to make and use the same.

10 This invention relates to machines of the kind that are used for plaiting a strip of sheet material and then pressing the plaits of the strip tightly together.

15 The main object of my invention is to provide a plaiting and compressing machine that is compact, inexpensive to construct and of such design that it can be run successfully at a high speed.

20 Another object is to provide a machine that will plait and compress a strip of paper in such a manner that the plaits will remain folded or pressed together for a considerable time after the compressed strip is removed from the machine.

25 And still another object is to provide an efficient plaiting and compressing machine that can be easily adjusted to adapt it to strips of different widths. Other objects and desirable features of my invention will be 30 hereinafter pointed out.

Briefly described, my improved machine consists of a pair of toothed plaiting rolls between which the strip to be plaited is passed, means for heating one or both of said 35 plaiting rolls so as to cause the strip to be heated during the operation of plaiting same, means for feeding a strip of paper or other similar sheet material into position to be engaged by said plaiting rolls, a compressing mechanism consisting of two elements, one of which moves relatively to the other so as to exert pressure on the plaited strip in a direction to press the plaits of same tightly together, and an ejecting 40 device for discharging the compressed strip from the machine. The compressing mechanism is separate and distinct from the plaiting rolls and from the means that feeds the strip to said plaiting rolls, and is so constructed that it will compress the heated 45 plaited strip edgewise and hold said strip

in its compressed condition so as to "set" the plaits of the strip or subject the strip to such treatment that the plaits will tend to remain together when the strip is removed 55 from the machine.

Figure 1 of the drawings is a side elevational view of the right hand side of a machine constructed in accordance with my invention.

Figure 2 is a side elevational view of the left hand side of the machine.

Figure 3 is a detail sectional view, illustrating one means that can be used for adjusting the oscillating member of the compressing mechanism.

Figure 4 is a vertical longitudinal sectional view of the machine.

Figure 5 is a top plan view of the machine with the top plaiting roll removed.

Figure 6 is an enlarged vertical longitudinal sectional view of the machine, showing the oscillating member of the compressing mechanism in its elevated position.

Figure 7 is a longitudinal sectional view 75 of one of the plaiting rolls, illustrating the means that is used for heating same.

Figure 8 is a view similar to Figure 6, showing the parts in a different position; and

80 Figures 9 and 10 are detail views, illustrating the construction and operation of the latches that are used for locking the "setting member" that holds the strip in its compressed condition during the return 85 stroke of the oscillating member of the compressing mechanism.

Referring to the drawings which illustrate the preferred form of my invention, A designates the bed plate of the machine, B designates two vertically-disposed side members on said bed plate which carry the main elements of the machine and C designates a horizontally-disposed table arranged between the side members B. The plaiting mechanism of the machine preferably consists of two rolls 1 and 2 arranged one above the other and provided with longitudinally-disposed, parallel teeth 1^a and 2^a which are so proportioned that they mesh with each other, the entire outer surface of each of said rolls being fluted, toothed or ribbed.

The rolls 1 and 2 are journaled in bearings on the side members B, and means is provided for causing said rolls to rotate continuously when the machine is in operation, 5 the means herein illustrated for this purpose consisting of a drive shaft 3 provided with a pinion 4 (shown in broken lines in Figure 1) that meshes with a gear 5 secured to one end of the bottom roll 2. One of the plaiting rolls is heated, preferably by an electrically-operated heating element D, so as to cause the strip to be heated during the operation of plaiting the strip. The heating element of the machine herein illustrated is 10 arranged inside of the bottom roll 2 and consists of a resistance wire 6 wrapped around a core 7 connected to a plug 8 which is screwed into one end of the roll 2, as shown in Figure 7. Electric current is supplied to the heating element D by brushes 9 connected to an electric supply circuit 10 and arranged so that they will bear upon a conducting ring 11 to which the resistance wire 6 is connected. It will, of course, be understood 15 that any other suitable means could be used for heating either one or both of the plaiting rolls without departing from the spirit of my invention.

The means that I prefer to use for feeding the strips of paper or other sheet material that are to be plaited, into position to be acted upon by the plaiting rolls consists of a plurality of endless sprocket chains 12 that travel over sprocket wheels 13 on two 20 horizontally-disposed shafts 14 which are mounted in the side members B of the frame of the machine, the table C being slotted so as to receive said chains and each of said chains being provided with a plurality of 25 projections 15, as shown in Figure 4, that are adapted to engage a strip α lying on the table C, as shown in Figure 5, and feed said strip rearwardly into position to be engaged by the rolls 1 and 2. The sprocket chains 30 of the strip feeding mechanism move continuously when the machine is in operation and are driven by a gear 16 on one of the sprocket wheel shafts 14 that meshes with an idler arranged under the gear 16 and secured to an idler 17, which, in turn, meshes 35 with a gear 18 on the left hand end of the plaiting roll 2, as shown in Figure 2. A feeding mechanism of the construction above described is desirable, in that it enables the 40 machine to be run at a much higher speed than is possible with a reciprocating feeding mechanism and it gives the operator more latitude in arranging the strips on the feed table, due, of course, to the fact that the 45 constantly moving chains are provided with a plurality of sets of feeding projections 15. The teeth of the rolls 1 and 2 mesh with each other so that the rotary movement of 50 said rolls will cause the strips to be fed rearwardly between said rolls, and in order 55 that the plaited strips will not stick to the heated roll 2, I have combined a stripping mechanism with the bottom roll 2, said stripping mechanism consisting of pieces of wire or small rods 15^a arranged in annular grooves 60 in the roll 2, as shown in Figure 8 and connected at their front and rear ends, respectively, to the table C and to the stationary guideway member of the compressing mechanism.

A compressing mechanism is arranged at the rear of the plaiting rolls for exerting pressure on the plaited strips in a direction to press the plaits of same tightly together. Said compressing mechanism comprises a 65 movable member, preferably an oscillating member E, arranged at the rear of the plaiting rolls, as shown in Figures 4, 6 and 8, and provided with a projection 19 that cooperates with a jaw 20 to compress the 70 plaited strips α' edgewise. The projection 19 is formed by a transversely-disposed bar that is set in a channel or groove in the convexed face of the member E. Said projection is capable of moving relatively to 75 the member E, and it is backed up by coiled expansion springs 19^a that normally hold it projected, as shown in Figure 6. The oscillating member E is of substantially segmental form and is of approximately the 80 same length as the plaiting rolls. Said member is carried by arms 21 on an oscillating shaft 22 that is journaled in the side members B of the frame of the machine, said shaft being rocked intermittently when 85 the machine is in operation, preferably by a link 23 which is pivoted at its upper end to an arm 24 on the end of said shaft and pivoted at its lower end to a gear 25 which meshes with the gear 18 on the left hand end 90 of the plaiting roll 2, as shown in Figure 2. If desired, the arm 24 can be adjustably connected to the shaft 22, so as to enable the stroke of the member E to be changed so as to vary the pressure which the parts 19 95 and 20 exert on the strip. One type of adjusting means that can be used for this purpose consists of a set screw 24^a for clamping the arm 24 to the rock shaft 22 and adjustable stop screws 24^b in said arm arranged 100 on opposite sides of a rib on said shaft, as shown in Figure 3. The projection 19 on the oscillating member E and the jaw 20 with which said projection cooperates both 105 extend transversely of the machine and are of approximately the same length as the plaiting rolls. The jaw 20 is preferably mounted in such a manner that it will move 110 slightly in the direction in which the projection 19 moves during the compressing operation, so as to increase the time that the compressed strip is clamped between the projection 19 and jaw 20. In the machine here-

in shown the lower end of the jaw 20 is hinged or pivotally connected at 26 to depending arms 27 on a stationary guideway member 28 which extends transversely of the machine at the rear of the plaiting roll 2 and the top surface of said guideway member 28 is slightly concaved so that it will conform approximately to the convexed surface of the oscillating member E, and thus serve as a supporting surface for the plaited strip α' when said plaited strip is being moved into engagement with the jaw 20 at the lower end of the guideway member 28.

15 The oscillating member E is provided with feeding devices 29 arranged so that they will engage a plaited strip that projects rearwardly from the plaiting rolls, as shown in Figure 6, move said plaited strip downwardly over the guideway member 28 into engagement with the jaw 20 and then clear or pass over the upper end of said jaw 20 during the last portion of the downward stroke of the member E. In the form of my invention herein illustrated the feeding devices 29 are slidingly mounted in slots in the oscillating member E and are connected to a transversely-disposed bar 30 which is carried by pivotally mounted rock arms 31 on the member E, said bar 30 being acted upon by springs 32, shown in Figures 6 and 8, that normally exert pressure on said bar in a direction tending to hold the feeding devices 29 projected, or, in other words, in such a position that they extend beyond the convexed surface of the member E. During the downward stroke of the member E the free ends 31^a of the rock arms 31 engage cam plates 33 on the side members B of the frame of the machine which are so disposed that the bar 30 will be moved sufficiently to retract the feeding devices 29 or render them inoperative after said feeding devices have moved the plaited strip into engagement with the jaw 20, said cam plates 33 being so designed that said feeding devices will be held in their retracted position until they clear the upper end of the jaw 20 on the forward or upward stroke of the member E.

50 As previously stated, the jaw 20 is so constructed that it will yield slightly during the compression stroke of the member E. Preferably, means is provided for varying the time at which the jaw 20 starts to move rearwardly and for varying the degree of movement of said jaw. In the form of my invention herein illustrated the jaw 20 is combined with guide rods 34 (see Figure 8) that project rearwardly from the stationary guideway member 28. The guide rods 34 pass loosely through the member 28 and the rear ends of said rods are screwed into holes in the jaw 20, lock nuts being mounted on the ends of said guide rods at the rear of the jaw 20, so as to prevent said rods from turning relatively to said jaw. Coiled expansion springs 35 which are arranged in pockets in the guideway member 28 between the bottoms of said pockets and heads 34^a on the guide rods 34 normally exert pressure on the jaw 20 in a direction to force said jaw forwardly or towards the guideway member 28. During the compressing operation the springs 35 yield sufficiently to permit the jaw 20 to move rearwardly into the position shown in Figure 8. At this point in the cycle of operations of the machine, namely, after the springs 35 have been compressed, the jaw 20 is engaged and locked in its rearward position by a locking means which will be hereinafter described. The rearward movement of the jaw 20 is limited by adjustable stops 20^a on the member 28 that pass freely through the jaw 20, (see Figures 9 and 10). If it is desired to vary the time that the jaw 20 starts to move rearwardly with the projection 19 on the member E during the compression stroke of said member, thus varying the degree of compression on the plaited strip, the guide rods 34 can be screwed into or out of the jaw 20, so as to vary the tension of the springs 35. By screwing said guide rods further into the jaw 20 the tension of the springs 35 will be increased, and accordingly, the jaw 20 will not start to move rearwardly until a later period in the compression stroke of the member E. When said guide rods are backed off or screwed further out of the jaw 20, the tension of the springs 35 will be reduced, and accordingly, the jaw 20 will start to move rearwardly at an earlier period in the compression stroke of the member E. When it is desired to handle relatively wide strips in the machine, the stops 20^a which limit the rearward movement of the jaw 20 are backed off or turned in such a direction that the heads on said stops are positioned farther away from the guideway member 28. This permits the jaw 20 to move rearwardly farther, and consequently, makes it possible to compress wide and narrow strips approximately the same degree. The locking means which holds the jaw 20 in its rearward position may consist of pivotally mounted locking devices 36 on the side members B of the frame of the machine which are provided at their front ends with hooks or notches that co-operate with lateral projections 37 on the ends of the jaw 20. When the jaw 20 is in its normal position, as shown in Figure 6, the lateral projections 37 at the ends of same are so arranged that they are just out of engagement with the notches in the front ends of the locking devices 36, and when said jaw moves rearwardly into the position shown in Figure 8, the locking devices 36 move upwardly under

the influence of springs 38, thus causing the projections 37 to be positioned in the notches in said locking devices, and consequently, holding the jaw 20 in its rearward 5 position.

After the strip has been compressed between the parts 19 and 20 it is maintained in its compressed condition for an instant or two more, so as to cause the plaits of the 10 strip to be "set," and in order that this may be accomplished without reducing the speed of the machine, means is provided for engaging the compressed strip and holding it in its compressed condition while the oscillating member E of the compressing mechanism is moving upwardly to carry the projection 19 thereon away from the jaw 20. In the machine herein illustrated a setting member consisting of a plate 39 is arranged 15 transversely of the machine at the lower end of the guideway member 28 between said member and the jaw 20 for co-operating with said jaw to hold the strip in its compressed condition during the return stroke 20 of the member E, said plate 39 being carried by a transversely-disposed bar 40 which is mounted in the guideway member 28 in such a manner that it can move upwardly and downwardly. The bar 40 is carried by a plurality of guide pins 41 in the member 28 whose lower ends are acted upon by coiled expansion springs 42 which normally exert pressure on said pins in a direction to move the bar 40 upwardly. Means is provided for 25 normally locking the bar 40 in its depressed position so as to hold the upper edge of the plate 39 and the upper ends of the pins 41 flush with or below the concaved surface on the guideway member 28 over which the 30 plaited strip α' is moved when the oscillating member E moves downwardly, and while said means can be formed in various ways without departing from the spirit of my invention, I prefer to equip the machine 35 with a locking mechanism composed of pivotally mounted latches 43 arranged at the opposite ends of the guideway member 28 and combined with springs 44, herein shown as leaf springs, that move the upper or free 40 ends of the latches 43 forwardly so as to hold shoulders or projections 43^a on said latches in engagement with the end portions of the bar 40 which carries the plate 39. During the downward movement of the oscillating member E, tripping devices 45 on 45 said member E that are arranged at the ends of same engage projections 46 on the extreme upper ends of the latches 43 and swing said latches rearwardly sufficiently to disengage 50 the shoulders 43^a thereon from the bar 40 (see Figure 10). The setting member or plate 39 will now be released, but said plate will not move upwardly, due to the fact that the plate 39 is then positioned directly underneath the projection 19 which is clamping 55

the compressed strip against the jaw 20, the side friction which the projection 19 exerts on the compressed strip being sufficient to overcome the force of the springs 42, notwithstanding the fact that the springs 42 are 70 stronger than the springs 19^a which hold the part 19 projected beyond the convexed surface of the member E. The instant the oscillating member E starts to move forwardly, thus relieving the side friction of 75 the projection 19 on the compressed strip, the springs 42 expand and move the pins 41 and the plate 39 upwardly, the projection 19 receding or moving inwardly into the channel in the member E, due to the fact that the 80 springs 42 are stronger than the springs 19^a which back up the projection 19. The result is that the setting member 39 will move into parallel relation with the jaw 20 and will co-operate with same to hold the strip compressed, as soon as the projection 19 on the member E starts to move away from the jaw 20. As the member E approaches its elevated position fingers 47 that project from the lower edge of said member strike against 90 the upper ends of the pins 41 which then protrude from the concaved surface of the guideway member 28 and move said pins downwardly, thus causing the plate 39 to be depressed and locked automatically in its 95 depressed position when the bar 40 moves downwardly sufficiently to permit the latches 43 to swing forwardly into engagement with the end portions of said bar.

Before the compressed strip is released 100 from the jaw 20 and the setting member 39 by the depression of said setting member, an ejecting mechanism operates to discharge the compressed strip into a discharge chute 48 (see Figure 4). Said ejecting mechanism 105 preferably consists of a horizontally disposed, rotatable shaft 49 provided with ejecting fingers 50 that travel upwardly through slots or cut out portions 51 in the upper edge portion of the jaw 20, one of said 110 slots or cut out portions 51 being shown in Figure 6. The shaft 49 of the ejecting mechanism rotates continuously when the machine is in operation and is preferably driven by a gear 54 on one end of said shaft that 115 meshes with a pinion 53 on the drive shaft 3, as shown in Figure 1 of the drawings. The constantly rotating shaft 49 of the ejecting mechanism also performs another function, namely, it trips the latches 36 which hold 120 the jaw 20 in its rearward position, the automatic release of said jaw 20 being effected by tripping devices 52 on the ejecting shaft 49 which engage the latches 36 and depress said latches into the position shown in Figure 6 125 after the compressed strip has been discharged from the jaw 20 and the setting member 39 by the ejecting devices 50.

The operation of my improved machine is as follows: The strip α that is to be plaited 130

and compressed is arranged transversely of the table C of the machine, as shown in Figure 5, and is thereafter moved rearwardly towards the plaiting rolls by the projections 5 15 on the sprocket chains 14. As soon as the strip has been engaged by the rolls 1 and 2 the rotary movement of said rolls feeds the strip rearwardly and causes longitudinally-disposed plaits or flutes to be formed in the 10 strip, thus producing a plaited strip α' , as shown in Figure 6. The oscillating member E then moves downwardly from the position shown in Figure 6, and when the feeding devices 29 on the member E engage the plaited 15 strip they cause said strip to be fed downwardly over the stationary guideway member 28 into engagement with the jaw 20. Just before the feeding devices 29 reach the jaw 20 said feeding devices are retracted or 20 withdrawn from the convexed surface of the member E by the engagement of the ends 31^a of the rock arms 31 with the stationary cam plates 33 on the side members of the frame of the machine. When the projection 25 19 on the member E engages the front edge of the plaited strip said projection 19 co-operates with the jaw 20 to press the plaits or folds of the strip tightly together, the jaw 20 yielding slightly during the last portion 30 of the compression stroke of the member E, due to the force which is exerted on said jaw by the member E and said jaw becoming locked automatically when it reaches its rearward position, as shown in Figure 8. 35 During the compression stroke of the oscillating member E the tripping devices 45 on said member engage the latches 43 and move said latches rearwardly into the position shown in Figure 10, thus causing the transversely-disposed plate or setting member 39 40 to be released from the means that normally holds said plate in its depressed position. As soon as the oscillating member E starts to move forwardly on its return stroke, the plate 45 39 moves upwardly into parallel relation with the jaw 20, so as to co-operate with same to hold the compressed strip in its compressed condition while the member E continues on its return stroke. After the 50 compressed strip has been ejected into the discharge chute 48 by the fingers 50 on the rotating shaft 49 of the ejecting mechanism, the fingers 47 on the member E engage and depress the pins 41 connected to the bar 40 55 which carries the setting member 39, and when the projections 52 on the ejecting shaft engage and depress the locking devices 36, the jaw 20 moves forwardly back to its normal position under the influence of the 60 springs 35 combined with the guide rods 34 that pass through the jaw 20.

A machine of the construction above described is compact, it can be manufactured at a low cost, it can be operated at a high speed and as it heats the strip during the

plaiting operation and immediately thereafter compresses the strip and holds it under compression for a considerable period, the plaits of the strip will remain folded or pressed together for a long time after the 70 strip is removed from the machine.

Having thus described my invention, what I claim as new and desire to secure by Letters Patent, is:

1. In a plaiting and compressing machine, 75 the combination of a means for plaiting and simultaneously heating a strip of sheet material, and a means for compressing said strip edgewise so as to press the plaits of same together.

2. In a plaiting and compressing machine, 80 the combination of a means for plaiting a strip, a means for heating said strip while it is being plaited, a means for compressing said strip edgewise while it is still heated, 85 and a means for maintaining said strip in its compressed condition long enough to set the plaits of same.

3. A plaiting and compressing machine, 90 comprising a pair of toothed rolls between which a strip is adapted to be passed, means for heating one of said rolls, means for preventing the strip from sticking to the heated roll, and a compressing mechanism arranged at the rear of said rolls for pressing the 95 plaits of the strip together and holding the strip under compression for an interval so as to set the plaits of same.

4. A plaiting and compressing machine, 100 comprising a pair of toothed rolls between which a strip is adapted to be fed by the rotary movement of said rolls, means for heating one of said rolls, annular grooves in the periphery of the heated roll, stripping devices in said grooves for preventing the 105 strip from sticking to said roll, and means arranged at the rear of the rolls for compressing the strip edgewise so as to press the plaits of same together.

5. A plaiting and compressing machine, 110 comprising a plaiting means, means for feeding a strip to said plaiting means, and a compressing mechanism separate and distinct from said plaiting means and said feeding means and operating independently of said 115 means for compressing the plaited strip edgewise so as to press the plaits of same together.

6. A plaiting and compressing machine, 120 comprising a pair of toothed rolls between which a strip is adapted to be passed, means for feeding a strip into position to be engaged by said rolls, the rotary movement of said rolls causing the strip to pass between same, and a compression mechanism operating independently of said rolls and said feeding means for pressing the plaits of the strip together after the strip has been discharged from said plaiting rolls.

7. A plaiting and compressing machine, 130

- comprising toothed rolls between which a strip is adapted to be passed; means for heating one of said rolls, means for feeding a strip into position to be engaged by said rolls, the rotary movement of said rolls causing the strip to pass between same, and a compressing mechanism operating independently of said plaiting rolls and independently of said feeding means for compressing the plaited strip edgewise so as to press the plaits of same together. 5
8. A plaiting and compressing machine, comprising means for plaiting a strip of thin sheet material, a compressing mechanism that acts on the plaited strip and presses the plaits of same together; and means for enabling said compressing mechanism to be adjusted so as to cause it to compress strips of various widths substantially the same degree. 15
9. A plaiting and compressing machine, comprising means for plaiting a strip, a compressing mechanism separate and distinct from said plaiting means for pressing the plaits of the strip together, comprising two co-operating parts, one of which moves towards and away from the other at each cycle of operations of the machine, and means for holding the strip in its compressed condition while one of said parts is separating from the other part. 25
10. A plaiting and compressing machine, consisting of a plaiting mechanism for forming plaits in a strip of material; a compressing mechanism for pressing the strip edgewise comprising two co-operating parts, one of which is adapted to move towards and away from the other, and a member that moves automatically into operative relationship with one of said parts so as to hold the compressed strip in its compressed condition when said parts are separated at the completion of the compressing operation. 35
11. A plaiting and compressing machine, comprising means for simultaneously heating and plaiting a piece of sheet material, a mechanism for compressing the plaits of said piece together while said piece is still heated comprising two co-operating parts, one of which moves towards and away from the other, a member that moves automatically into operative relationship with one of said parts to hold the plaits of said piece of material tightly together when said parts are separated at the completion of the compressing operation, and an ejecting device for discharging said plaited piece of material from the machine. 45
12. A plaiting and compressing machine, consisting of a plaiting mechanism for forming plaits in a strip, a compressing mechanism for compressing the plaits of the strip together comprising a jaw and a part that moves towards and away from said 50
- jaw, means for causing said jaw to move with said part during the compression stroke of said part, and means that co-operates with said jaw to hold the strip under compression during the return stroke of said part. 55
13. A plaiting and compressing machine, comprising means for plaiting a strip, a compressing mechanism for pressing the plaits of the strip together comprising a jaw and a movable part that moves towards and away from said jaw, means for permitting said jaw to move in unison with said part during the last portion of the compression stroke of said movable part, and means for enabling the time at which said jaw starts to move to be varied. 60
14. A plaiting and compressing machine, comprising means for plaiting a strip, a compressing mechanism for pressing the plaits of the strip together comprising a jaw and a movable part that moves towards and away from said jaw, means for permitting said jaw to move in unison with said part during the last portion of the compression stroke of said movable part, and an adjustable means for limiting the degree of movement of said jaw. 65
15. A plaiting and compressing machine, comprising toothed rolls between which a strip is adapted to be passed, a compressing mechanism arranged at the rear of said rolls and comprising an abutment against which the plaited strip is adapted to be forced, and a pivotally mounted oscillating member for forcing the strip against said abutment so as to press the plaits of the strip together. 70
16. A plaiting and compressing machine, comprising mechanism for plaiting a strip, a compressing mechanism comprising an abutment, and a movable member provided with a feeding device that is adapted to engage the plaited strip and move it towards said abutment and also equipped with a part, separate and distinct from said feeding device, that compresses the strip edgewise against said abutment. 75
17. A plaiting and compressing machine, comprising mechanism for plaiting a strip, a compressing mechanism comprising an abutment, a movable member provided with a feeding device that is adapted to engage the plaited strip and move it towards said abutment and also equipped with a part, separate and distinct from said feeding device, that compresses the strip edgewise against said abutment, and means for rendering the feeding device on said movable member inoperative after the strip has been moved into engagement with said abutment. 80
18. A plaiting and compressing machine, comprising means for plaiting a strip, a compressing mechanism provided with an abutment, a movable member having a part 85

- that travels over said abutment, a feeding device projecting from said member for engaging the plaited strip and moving it towards said abutment, means on said member 5 for compressing said strip edgewise against said abutment, and means for retracting said feeding device so as to permit it to clear said abutment during the operation of said movable member.
- 10 19. A plaiting and compressing machine, comprising plaiting rolls between which a strip is adapted to be passed, a compressing mechanism at the rear of said plaiting rolls comprising an abutment and an oscillating member provided with a projection that is adapted to co-operate with said abutment to compress the plaited strip edgewise, feeding devices on said oscillating member for moving the plaited strip towards said abutment, 15 a resilient means for holding said feeding device projected beyond the face of said oscillating member, rock arms combined with said feeding devices, and stationary cam plates arranged in such a manner that 20 said rock arms will engage same and thus retract said feeding devices during the compression stroke of said oscillating member.
- 20 20. A plaiting and compressing machine, comprising plaiting rolls between which a strip is adapted to be passed, a compressing mechanism arranged at the rear of said plaiting rolls and comprising a jaw and an oscillating member provided with a projection that co-operates with said jaw to compress the plaited strip edgewise, said jaw being pivotally mounted, a resilient means 25 combined with said jaw for normally holding it in a certain position, means for locking said jaw after it has been moved into a certain position during the compression stroke of said oscillating member, and a setting member that co-operates with said jaw to maintain the compressed strip in its compressed condition during the return 30 stroke of said oscillating member.
- 25 21. A plaiting and compressing machine, comprising toothed plaiting rolls between which a strip is adapted to be passed, a guideway member arranged at the rear of said rolls, a pivotally mounted abutment or jaw arranged at the lower end of said guideway member, an oscillating member arranged above said guideway member and provided with a part that co-operates with 35 said jaw to compress the plaited strip edgewise, a resilient means combined with said jaw in such a manner that it will permit said jaw to yield rearwardly slightly during the compression stroke of said oscillating member, means for automatically locking said jaw in its rearward position, a setting member that co-operates with said jaw to hold the compressed strip in its compressed condition during the return stroke of said 40
- 45 oscillating member, means for ejecting the strip from said jaw and setting member, and means for thereafter releasing the jaw from said locking means.
- 50 22. A plaiting and compressing machine, comprising plaiting rolls between which a strip is adapted to be fed, a guideway member arranged at the rear of said rolls and provided with a hinged jaw, an oscillating member provided with a projection that is adapted to co-operate with said jaw to compress the plaited strip edgewise, a setting member arranged in proximity to said jaw, and means for causing said setting member to move into such a position that it co-operates with said jaw to hold the compressed strip in its compressed condition during the return stroke of said oscillating member.
- 55 23. A plaiting and compressing machine, comprising plaiting rolls between which a strip is adapted to be fed, a guideway member arranged at the rear of said rolls and provided with a hinged jaw, an oscillating member provided with a projection that is adapted to co-operate with said jaw to compress the plaited strip edgewise, a setting member arranged in proximity to said jaw, means for causing said setting member to move into such a position that it co-operates with said jaw to hold the compressed strip in its compressed condition during the return stroke of said oscillating member, a resilient means combined with said jaw in such a manner that said jaw can yield rearwardly during the compression stroke of said oscillating member, and means for restoring said jaw and said setting member to their normal positions during the return stroke of said oscillating member.
- 60 24. A machine for plaiting and compressing a strip, comprising a plaiting mechanism, a guideway member over which the plaited strip is adapted to be fed, an oscillating member arranged above said guideway member and provided with a part that co-operates with a part carried by said guideway member to compress the strip edgewise, a spring-pressed setting member carried by said guideway member, a locking means for normally holding said setting member in a depressed position, and means for rendering said locking means inoperative during the compression stroke of said oscillating member.
- 65 25. A plaiting and compressing machine, comprising plaiting rolls, means for feeding a strip into a position to be engaged by said plaiting rolls, means for heating one of said rolls, a guideway member arranged at the rear of said rolls and provided with a yielding jaw, an oscillating member provided with a projection that is adapted to co-operate with said jaw to compress the plaited strip edgewise, springs for holding the pro-

jection on said oscillating member in its projected position, a spring-pressed setting member arranged in proximity to said jaw, a locking means for holding said setting member normally in a depressed position, means for rendering said locking means inoperative during the compression stroke of said oscillating member, means for locking

said jaw in its rearward position, an ejecting mechanism for discharging the compressed strip from the machine, and means operated by said ejecting mechanism for tripping the locking means that holds said jaw in its rearward position.

JOHN MAIER.
